PORTABLE CREDIT CARD IMPRINTER

Don I. Manners, 6210 N. Artesian, Chicago, Ill., and Jack Whedon, 5 Ridgewood Road, Elk Grove Village, Ill.
Filed Apr. 1, 1960, Ser. No. 19,383
10 Claims. (Cl. 101—269)

This invention relates generally to imprinter devices for recording indicia from embossed surfaces and more particularly, is concerned with providing a novel imprinter structure for use with credit cards and the like, said imprinter being portable and adapted to be carried upon the person of the user for operation directly at the site of a purchase.

Cards and the like, carrying thereupon identifying indicia in the form of embossed markings or protruding surfaces are widely utilized for credit purchases particularly at gasoline service stations and the like. These cards, generally made from stiff materials such as plastic or metal, are handed to the service station attendant at the time of purchase. The attendant then records the information contained thereon upon a pre-printed form, said form being then presented to the purchaser for his signature and then retained by the attendant for billing to the purchaser. Generally the information required is transferred to the invoice form by inserting the card into an imprinter device having pressure exerting means therein whereby the embossed indicia may be transferred as a marking to the invoice slip by the pulling of a lever secured to said pressure means, said action forcing ink impregnated tape or the like against the raised surfaces and thus transferring or printing the indicia from the raised surfaces to said invoice.

Devices of the character heretofore used for the above mentioned purposes have been heavy, cumbersome and must be permanently secured either to a wall or post, or to a heavy table whereby the main body of the imprinter is anchored to a substantial object so as to prevent upset during use.

A second, and perhaps greater disadvantage of prior imprinting devices is the requirement that the said devices must be located within the enclosed area of the service station itself to prevent exposure, theft or mishandling thereof. This requires the attendant to leave the customer at the gasoline pump island, which is the usual site of purchase, return to the service station and imprint the invoice there, then deliver the imprinted invoice back to the customer, return the card and obtain the customer's signature on said invoice. The invoice generally is presented to the customer for his signature upon a clipboard or the like hard surface. Not only does this process cause unnecessary activity for the attendant, but results in considerable delay for the customer and resulting unwarranted dissatisfaction with the performance of the service station attendants with accompanying loss of good will. Moreover, because of such delay, other customers are kept waiting for service and hence may be lost through no fault of the attendant.

Considerable expense is entailed in installing and maintaining the prior bulky and heavy devices at each of the gasoline pumping islands of said station, and even then the attendant must leave the customer to use the imprinter.

Accordingly, it is the primary object of the invention to provide a structure for a credit card imprinter which is light weight and portable, being adapted to be carried upon the person of an attendant or the like for use directly at the site of purchase without the attendant leaving the customer, said imprinter device substantially eliminating the disadvantages hereinabove enumerated.

Another object of the invention is to provide a port-

2

able credit card imprinter structure adapted to transfer indicia from embossed credit card surface to an invoice form or the like and which is capable of being operated while being held in the palm of the attendant's hand.

5 A further object of the invention is to provide a credit card imprinter construction which may be carried in a holster upon the person of an individual such as a gasoline service station or other attendant, and which may serve as a writing surface for the signature of the customer.

An additional object of the invention is the provision of a portable credit card imprinter structure wherein means are provided for the insertion of a credit card and an invoice form and wherein chemical or other roller means are provided for impressing the embossed indicia upon an invoice surface and transferring a mark thereon corresponding to the said embossed indicia, said imprinter being provided with guide means and handle means whereby the roller means may be drawn across the length of said invoice and returned to its original position, thereby permitting the signature of the customer to be impressed in the designated place and the subsequent removal of the completed invoice and the credit card.

25 Still other objects and advantages will become evident to the skilled artisan as the description proceeds. In accordance with the patent statute we have illustrated and described a preferred embodiment of our invention, although it should be obvious that various changes in 30 the size and minor details of the structure may be made without departing from the spirit of the invention.

Referring to the drawings in which the same characters of reference are employed to indicate corresponding or similar parts throughout the several figures of the drawings:

FIG. 1 is a top plan view of our portable credit card imprinter device illustrating the credit card and invoice in position for imprinting.

40 FIG. 2 is a sectional view taken along lines 2—2 of FIG. 1 and in the direction indicated.

FIG. 3 is a front end-on elevational view of the imprinter of FIG. 1 with a portion thereof shown in section to illustrate interior structure thereof.

45 FIG. 4 is enlarged fragmentary sectional view of said imprinter with the roller in printing position.

FIG. 5 is a reduced fragmentary view of the end wall of said tray showing modified end guide means.

The invention is generally concerned with providing a portable credit card imprinter particularly adapted for use by gasoline service station attendants although not limited thereto. Said imprinter is capable of being carried upon the person of the user as in a holster or the like so that said attendants may mark a pre-formed invoice at the vehicle being serviced without being required to go back into the service station to use an imprinting device there.

50 The device generally comprises a substantially rectangular metal tray, the bottom thereof having a flexible backing member with upstanding protrusions enabling the indexing of the credit card in a predetermined location therein. The credit card may be inserted into the device through a slot provided in the side of said tray. Roller means is provided which impress the paper invoice upon the embossed surface protrusions of the credit card and cause a marking to show through. The roller means are mounted upon a shaft which in turn moves along a track provided in the sides of said tray whereupon the roller is brought down flat and in pressure against the top of said invoice slip upon which the marking is desired. A wire bail or handle is provided secured to said roller as for example, to the ends of the shaft mounting same, for pulling the roller forward along the said track for imprinting. The front wall

of the tray may be provided with means for guiding said wire handle during the pulling thereof, and said latter means may also be provided with means for permitting the free end portion of the handle to be withdrawn from the tray so that the wire may be swung backwards to allow removal of the marked invoice form from the imprinter. It is apparent that the entire operation may be done with the tray being held in the palm of the attendant's hand. Means are also provided to lock the wire bail or handle in position when the imprinter is not in use.

Referring to FIG. 1 of the drawing wherein the imprinter embodying our invention is designated by reference character 10, said imprinter is shown with the credit card 12 and the blank invoice slip 14 being inserted in imprinting position thereon.

The imprinter 10 comprises a substantially rectangular tray 16 having vertical side walls 18 and end walls 22 and 24. The base or floor 20 of said tray 16 is lined with a layer 26 of a resilient material such as molded soft rubber, and said layer 26 is provided with a group of upstanding protrusions 28 which serve as stop members for indexing the credit card when same is inserted into said tray. These stop members also provide spacing between the invoice and the layer 26 so that the card 12 may be slipped therebetween. A slot 27 is provided in one of said walls 18 and is adapted to permit the passage of said credit card 12 into said tray 16, the card being inserted until it abuts the stop members 28. Embossed indicia 32 may be provided upon the layer 26 in a predetermined location adjacent the position of the embossed indicia contained on the credit card 12. This indicia 32 may be in the form of upraised rubber or metal type or printing blocks or the like and is generally utilized to convey the identifying indicia of the seller upon said invoice. An adjustable date stamp liner may also be utilized so that current dates may be inserted therein.

A pair of coextensive elongate slots 34 are provided along the length of said side walls 18, one in each said wall and said slots being parallel one to the other. Mounted in said slots at one end of said tray 16 adjacent wall 22 thereof is a shaft 36, said shaft being secured in place by washers 38 and fastening means 40 so that said shaft is movable along the length of said slots 34 across the entire length of the tray 16. Mounted for rotation upon said shaft 36 is a roller 42. Said roller 42 is formed from a non-frangible material such as soft rubber or felt or some synthetic resin which has been chemically treated or impregnated with a printing material such as ink or the like whereby when said roller is drawn against material which has been placed over an embossed surface, a marking corresponding to said embossed surface will be made upon said material. The roller is disposed closely adjacent one side wall of said tray so that as the shaft 36 is drawn across the tray 16, the roller comes into contact with the embossed surfaces of the credit card 12 and other protruding indicia, through the paper of the invoice slip 14. Wall 22 may also be provided with an outwardly extending flange (not shown) to shield the roller 42 when the latter is rest position.

The track formed by the slots 34 forces the shaft and roller 42 to be drawn across the length of the tray 16 so that the said roller 42 exerts a pressure against the said embossed surfaces. This is accomplished by having that part of the slot 34 which is designated 46 disposed parallel to but lower than portion 48 of said slot 34, the two portions being connected by portion 50 thereof.

It should be noted that the pressure exerted by the roller upon the invoice surface and against said embossed surfaces is sufficient to print markings representing said indicia upon the invoice primarily because of the resilient nature of the lining layer 26.

The means provided for pulling the shaft 36 and roller 42 across said tray comprises a U-shaped bail 52 having a looped handle 54 and ends 56 secured around said shaft adjacent both ends thereof and on the interior of

said tray 16. The bail 52 is formed from a spring wire, the ends thereof exerting a resilient force against the respective side walls 18 of the tray. The said bail 52 is threaded through a pair of spaced horizontal slots 58 and 58' formed in the front wall 24 of said tray so that when the looped handle 54 is pulled, the shaft 36 and its roller 42 are forced to follow the slot or guide means 34 with pressure being exerted by said roller upon the invoice slip against the embossed indicia 31 and 32. Vertical slots 60 and 62 are provided in said front wall 24 communicating with a respective one of the horizontal slots 58 and 58'. These latter slots 60 and 62 permit upraising of the bail 52 to permit removal of the imprinted invoice slip. The left portion of the bail 52 may be squeezed so that the arms thereof pass through the said slots 60 and 62, and the finished slip thus may be removed. Although shown in this embodiment as cooperating vertical and horizontal slots, an equivalent construction may be obtained by utilizing a pair of arcuate slots or paths formed in said front wall. Said front wall may also have a mid-portion 63 thereof blanked out leaving portions 65 and 66. In this case slots 58 and 58' would be in communication with one another, and slots 60 and 62 would be continuous with the such continuous slots 58 and 58', and, in actuality, would be a single wide slot, the walls thereof being either arcuate or straight.

From the description above the operation of the novel portable imprinting device should be apparent, however, a short description thereof for illustrative purposes in connection with gasoline service station credit purchases may be still in order. Initially the device may be readied for use by pre-insertion of a blank invoice form 16 therein by squeezing the bail 52 so that it passes through slots 60 and 62. The bail 52 is then replaced through said vertical slots to lie threaded through horizontal slots 58 and 58'. Thus loaded the device may be carried in a holster (not shown) adapted to be worn upon the person of the attendant as on a belt or the like. The imprinter may just as easily be worn unloaded, the blank invoice being placed therein at the time of use.

When a purchase is made, the credit card identifying the purchaser is handed to said attendant and inserted into the imprinter through the slot 27 provided therein. Then, for example, the quantity of gasoline purchased and the price is written upon said invoice in the space provided, the bail 52 is then drawn by the looped handle 54 so that the shaft 36 passes along the guide means track 34 with the roller 42 in pressure contact with the invoice over the embossed surfaces, the imprint being made, the bail then being pushed back to return the roller to original condition and the credit card withdrawn.

The tray containing the thus completed invoice is then presented to the customer for his signature, and after said signature is placed thereon, the attendant squeezes the bail 52, removes the invoice, perhaps after checking the signature thereon with that on the credit card for verification of identity, and gives the credit card and a copy of the invoice to the customer, retaining a copy for billing. The imprinter may then be reloaded with a fresh invoice and inserted in the "holster" ready for repeated use.

The invention may conceivably need only be used for the imprinting process; any handwritten notations, including the notations of amount of purchase, signature of purchaser, etc. being placed on the invoice after removal thereof from the imprinter device, utilizing the underside thereof as a support.

In describing the operation of our invention, a certain order of operational steps were described above. It should be clearly understood that the order so stated is not critical and some steps can be taken out of said order, interposed with others, or even left out without departing from the scope of the invention herein described.

The invention also conceivably may comprise a tray device wherein the floor portion 20, with its resilient layer 26 may be hinged to the rear wall 22, or even to portions

of the side walls 18 closely adjacent the right hand portion of slot 34. The front and rear walls of the tray may possibly be eliminated altogether, with the tray floor being separated from the slotted walls 18, and said removable tray having upstanding resilient clamp portions substituting for said walls 22 and 24.

The invention also contemplates that the entire credit card may be accommodated within the said imprinter device by increasing the width thereof. While the slot 27 may be convenient for inserting the credit card 12, said card may be merely placed upon the interior of the tray with the embossed area upraised, the card resting upon the resilient layer 26, with the invoice form placed over said card.

A substantial savings in time results from the convenience in utilizing the invention by conducting the entire transaction at the exact site of the transaction without leaving the customer, without returning to any main office, or other area, station, or going anywhere else to imprint said invoices. More important is the increased customer satisfaction resulting from speedy service obtainable through the use of our novel portable imprinter.

Although we have particularly shown our portable imprinter associated with use in a gasoline service station, it is obvious that our device is applicable to any use whereupon embossed indicia is desired to be imprinted upon a material and said imprinting device is desired to be carried upon the person of the individual using same.

It is believed that our invention, its mode of operation and construction and assembly, and many of its advantages should be readily understood from the foregoing without further description, and it should also be manifest that while a preferred embodiment of the invention has been shown and described for illustrative purposes, the structural details are nevertheless capable of wide variation within the purview of our invention as defined in the appended claims.

We claim:

1. A portable imprinter device for recording indicia from embossed surfaces of credit cards and the like and adapted to be carried upon the person of an individual and comprising, an open-topped tray member adapted to receive a credit card and blank invoice therein, said invoice being entirely within the tray, roller means for forming a visible mark representative of said indicia contained on said embossed surface, and means for passing said roller means in pressure contact with said embossed surface with the blank invoice therebetween, said latter means comprising spring-like free-ended grasping means for said roller means and pivotally mounted thereto, track means adapted to receive and guide said roller means along the length of said tray member, and guide means at one end of said tray cooperating with said track means to force the roller means along a pressure path to bring same in pressure contact with said blank invoice, said guide means comprising at least a pair of spaced L-shaped slots formed at one end of the tray, the upper ends of said slots opening to the said one end of said tray, said spring-like free-ended grasping means being threaded through said slots and adapted to be pulled back and forth across the length of said tray, said grasping means adapted to be removed from said slots when said roller means is disposed at the other end of said tray.

2. A structure as described in claim 1 in which said tray member is substantially rectangular in configuration and has upstanding vertical walls, and said track means is formed in a pair of said walls.

3. A structure as described in claim 1 wherein said tray is lined with a lining of non-frangible resilient material, and said lining is provided with a plurality of upstanding protrusions spaced at predetermined locations thereon.

4. A structure as described in claim 1 wherein said tray member has upstanding walls, and said track means comprises an elongate slot formed in each of a parallel

pair of said walls, said slots being parallel one to the other and co-extensive with the length of said pair of walls, a shaft mounted for movement along said slots, said roller means mounted for rotation upon said shaft, said shaft adapted to be pulled along said slots, a portion of said slots coextensive with said embossed surfaces being spaced closer to the floor of said tray than the remaining portion of said slots.

5. A portable imprinter device for recording indicia from embossed surfaces of credit cards and the like and adapted to be carried upon the person of an individual, said device comprising a tray for receiving a blank invoice slip, said tray having upstanding vertical walls, card receiving means formed in said tray, guide track means provided in the side walls of said tray, a shaft member mounted for movement along said track means, roller means mounted for rotation upon said shaft member and positioned therealong to pass over the embossed surfaces of said credit card, and means provided to move said shaft along said track means with the roller means brought into pressure contact with said blank invoice slip over said embossed surface to transfer a mark upon said invoice equivalent to the indicia represented by said embossed surfaces, said latter means comprising pull means secured to said roller means and slot means in one end of said tray adapted to have said pull means threaded therethrough, said slot means comprising a pair of spaced horizontal slots substantially co-planar with a portion of the track means and a pair of passageways formed in said end wall communicating between a respective one of said slots and the top of said wall, said pull means adapted to be received therethrough into communication with said horizontal slots.

6. A portable imprinter device for use in conjunction with credit cards and the like and adapted to transfer indicia represented by embossed surfaces of said cards to invoice slips, said imprinter device comprising a substantially rectangular tray member having upstanding vertical walls, slot means disposed in one of said side walls for insertion of said credit card, stop means disposed upon the floor portion of said tray to limit entry of said credit card therein, roller means mounted for rotation at one end of said tray, guide track means and means for moving said roller means along said track means whereby said roller means is brought into pressure contact with the embossed surface of said credit card with an invoice slip therebetween for marking said invoice slip with the indicia represented by said embossed surface, said track means comprising a pair of elongate slots formed in each of a pair of opposite walls of the tray coextensive with the length thereof, and said roller means comprises a shaft member mounted at one end of the tray for movement along said track means and a chemically impregnated roller member is mounted for rotation on said shaft closer to one of said side walls than the other, and a wire handle secured to the ends of said shaft on the interior of said tray, said handle adapted to draw the shaft along said slots to pass the roller in pressure contact with the said embossed surface with the invoice slip therebetween, wherein the front wall of said tray has a pair of spaced co-planar horizontal slots therein for passage of said handle therethrough and said wall is provided with a pair of spaced vertical slots one of each communicating with a respective horizontal slot, said handle being adapted to be squeezed whereby it can pass through said vertical slots to facilitate removal of said invoice.

7. A portable imprinter device for use in conjunction with credit cards and the like and adapted to transfer indicia represented by embossed surfaces of said cards to invoice slips, said imprinter device comprising a substantially rectangular tray member having upstanding vertical walls, slot means disposed in one of said walls for insertion of said credit card, stop means disposed upon the floor portion of said tray to limit entry of said credit card therein, roller means mounted for rotation at one end of

said tray, guide track means and means for moving said roller means along said track means whereby said roller means is brought into pressure contact with the embossed surface of said credit card within an invoice slip therebetween for marking said invoice slip with the indicia represented by said embossed surface, said track means comprising a pair of elongate slots formed in each of a pair of opposite walls of the tray coextensive with the length thereof, and said roller means comprises a shaft member mounted at one end of the tray for movement along said track means and a chemically impregnated roller member is mounted for rotation on said shaft closer to one of said side walls than the other, and said means for moving said roller means comprises a wire handle secured to the ends of said shaft on the interior of said tray, said handle adapted to draw the shaft along said slots to pass the roller in pressure contact with said embossed surface with the invoice slip therebetween.

8. A portable imprinter device for recording indicia from embossed surfaces of credit cards and the like and adapted to be carried upon the person of an individual, said device comprising a tray for receiving a blank invoice slip, said tray having upstanding vertical walls, card receiving means formed in said tray, guide track means provided in the side walls of said tray, a shaft member mounted for movement along said track means, roller means mounted for rotation upon said shaft member and positioned therealong to pass over the embossed surfaces of said credit card, and means provided to move said shaft along said track means with the roller means brought into pressure contact with said blank invoice slip over said embossed surface to transfer a mark upon said invoice equivalent to the indicia represented by said embossed surface, said latter means comprising spring-like free-ended pull means pivotally secured to said shaft member and slot means in one end of said tray adapted to have said pull means threaded therethrough, said slot means comprising a pair of spaced horizontal slots substantially co-planar with a portion of the track means and a pair of substantially vertical passageways formed in said end wall each communicating between a respective one of said slots and the top of said wall, said pull means adapted to be received therethrough into communication within said horizontal slots.

9. A portable imprinter device for recording indicia from embossed surfaces of credit cards and the like and adapted to be carried upon the person of an individual and comprising, an open-topped tray member adapted to receive a credit card and blank invoice therein, said invoice being entirely within the tray, roller means for forming a visible mark representative of said indicia contained on said embossed surface, and means for passing said roller means in pressure contact with said embossed surface with the blank invoice therebetween, said latter means comprising spring-like free-ended grasping means for said roller means and pivotally mounted thereto, track means adapted to receive and guide said roller means along the length of said tray member, and guide means at one end of said tray cooperating with said track means to force the roller means along a pressure path to bring same in pressure contact with said blank invoice, said spring-like free-ended grasping means comprising a bail of wire or the like of U-shaped configuration and having its ends pivotally secured to said roller means, said guide means comprises a horizontal passageway formed at one end of said tray and a substantially wider vertical passageway also formed at said one end of said tray in

communication with the horizontal passageway between the ends thereof, said bail threaded through said passageways, said tray having a pair of vertical side walls, and said track means is formed in said side walls and comprises a pair of elongate slots each formed in one of said side walls, said slots being parallel one to the other, said slots being positioned lower at said one end than at the opposite end of said tray, said roller means being adapted to be passed over said embossed surface in pressure contact therewith by pulling said bail outward through said passageways in said one end, said roller means being mounted in said slots so as to follow same while being pulled across the length of said tray, and said roller means adapted to be returned to its original position in like manner.

10. A portable imprinter device for recording indicia from embossed surfaces of credit cards and the like and adapted to be carried upon the person of an individual and comprising, an open topped tray member adapted to receive a credit card and blank invoice therein, said invoice being entirely within the tray, roller means for forming a visible mark representative of said indicia contained on said embossed surface, and means for passing said roller means in pressure contact with said embossed surface with the blank invoice therebetween, said latter means comprising spring-like free-ended grasping ends for said roller means and pivotally mounted thereto, said means adapted to receive and guide said roller means along the length of said tray member, and guide means at one end of said tray cooperating with said track means to force the roller means along a pressure path to bring same in pressure contact with said blank invoice, said spring-like free-ended grasping means comprising a bail of wire or the like of U-shaped configuration and having its arms pivotally secured to said roller means, and said guide means comprising at least a pair of spaced L-shaped slots formed at one end of said tray and being in mirror image relation one to the other with the vertical legs thereof facing one another, said bail being threaded through said passageways, said tray having a pair of vertical side walls and said track means is formed in said side walls and comprises a pair of elongate slots each formed in one of said side walls, said slots being parallel one to the other, said slots being positioned lower at said one end than at the opposite end of said tray, said roller means being adapted to be passed over said embossed surface in pressure contact therewith by pulling said bail outward through said passageways in said one end, said roller means being mounted in said slots so as to follow same while being pulled across the length of said tray, and said roller means adapted to be returned to its original position in like manner.
